UNITED STATES PATENT OFFICE

145,002

DESIGN FOR A COMBINATION MAIL BOX AND MAGAZINE AND NEWSPAPER RACK

Carl W. Bierig, Joplin, Mo.

Application November 7, 1945, Serial No. 123,519

Term of patent 14 years

(Cl. D74—9)

To all whom it may concern:

Be it known that I, Carl W. Bierig, a citizen of the United States, residing at Joplin, in the county of Jasper and State of Missouri, have invented a new, original, and ornamental Design for a Combination Mail Box and Magazine and Newspaper Rack, of which the following is a specification, reference being had to the accompanying drawings, forming part thereof.

Figure 1 is a front elevational view of a combination mail box and magazine and newspaper rack showing my new design.

Figure 2 is an end elevation of the same, observing it from either end.

Figure 3 is a rear elevation of Figure 1 or a view observing Figure 2 in a direction from left to right.

Figure 4 is a top plan view based on Figure 3.

The invention has to do with a unitary structure characterized by a multiple lid equipped mail box having transparent windows in its front, and a flanged shelf on the rear, said shelf constituting newspaper and magazine rack.

I claim:

The ornamental design for a combination mail box and magazine and newspaper rack, as shown and described.

CARL W. BIERIG.
